UNITED STATES PATENT OFFICE.

WILLIAM M. WILKIN, OF ERIE, PENNSYLVANIA.

BAND-SAW MILL.

SPECIFICATION forming part of Letters Patent No. 406,323, dated July 2, 1889.

Application filed January 31, 1889. Serial No. 298,271. (No model.)

To all whom it may concern:

Be it known that I, WILLIAM M. WILKIN, a citizen of the United States, residing at Erie, in the county of Erie and State of Pennsylvania, have invented certain new and useful Improvements in Band-Saw Mills; and I do hereby declare the following to be a full, clear, and exact description of the invention, such as will enable others skilled in the art to 10 which it appertains to make and use the same.

This invention relates to band-saw mills; and it consists in certain improvements in the construction of the same, as will be herein-after fully set forth, and pointed out in the 15 claims.

My invention is illustrated in the accompanying drawings, as follows:

Figure 1 is a vertical section on the line of the band-wheel shafts. Fig. 2 is a vertical 20 section on the line $x x$, which is at right angles to the band-wheel shafts.

The construction is as follows:

A A' mark the upper frame-work of the mill, which is constructed as shown in an application for a patent now pending filed by 25 me, and forms no part of the present invention.

B are vertically-movable posts, which move in the upright frame-posts A' and rest on a 30 cross-bar G.

C are vertically-movable caps, which set on top of the posts B.

D is the upper band-wheel shaft, which is journaled in boxes E, which are pivoted on 35 the caps C.

F are vertically-movable bars, which are contained within the posts B, and are movable vertically with and also independently of said posts B, so as to support the caps C, while 40 their lower ends rest on levers K, which are fulcrumed on knife-edges g on the bar G, the posts B being recessed at their lower ends to receive the ends of said levers K. The long ends of the levers K are connected with a 45 weight-lever K' by a link k.

H H are screws which set under the bar G, and are operated by nuts H', which are turned by the worm-shaft M and worm-gear L, so as to move simultaneously, the screws H being 50 held against turning by being chisel-formed at their upper ends. As the screws H H are operated, the bar G, posts B, levers K K, and

K', weight W, bars F, caps C, boxes E, and shaft D all move *en masse* vertically. As the levers K are moved, the bars F, caps C, boxes 55 E, and shaft D alone are moved vertically.

Of the last-named parts the levers K K and K' and bars F are for giving tension to the saw, while the screws H, the worm-gearing by which the said screws are moved, and the 60 posts B are for adjusting the upper band-wheel P' to the length of the saw.

It will be observed that the means for giving tension to the saw move independently of the means for adjusting the band-wheels to 65 the saw, but are at the same time movable with the same, and also that all of these movable parts act independent of the frame-work, which is fixed.

The vertically-movable posts B, with the 70 contained independently-movable bars F, constitute, in effect, extensible vertically-movable supports within the fixed frame-posts A' for the upper band-wheel shaft, and the extensibility of these supports is regulated automatically.

I do not desire to be limited to the use of the levers and weights as the means for effecting the tensional action of the extensible supports, as it is obvious that other well-known 80 means for this purpose may be substituted.

What I claim as new is—

1. In a band-saw mill, the combination, with the fixed frame-work A A' A', and the vertically-adjustable yoke G, contained within the 85 frame-work A, of automatically extensible supports for the upper band-wheel shaft contained with the frame-work A' A' and supported by said yoke.

2. In a band-saw mill, the combination, with 90 the fixed frame-work A A', of the yoke or bar G, posts B, seated on said yoke, sliding caps C on said posts, boxes E on said caps, and screws H, for vertically moving said yoke or bar.

3. In a band-saw mill, the combination, with 95 the fixed frame-work A A', of the yoke G, posts B, seated on said yoke, sliding caps C on said posts, boxes E on said caps, bars F within said posts B and supporting said caps, levers K, fulcrumed on said yoke and supporting 100 said bars F, weight-lever K', fulcrumed on said yoke and connected with said levers K, and screws H, for vertically moving said yoke.

4. In a band-saw mill, the combination, with

the hollow horizontal frame-piece A and the hollow vertical frame-pieces A', of the yoke G, contained within the frame-piece A, the posts B, contained within the vertical frame-pieces A' and resting on said yoke, a lifting apparatus supported by said frame-piece A, which vertically moves said yoke G and posts B, scale-gearing supported on said yoke, vertical bars F within said posts B, which are moved 5 to by said scale-gearing, sliding caps C on said posts B, which rest on said bars F, and boxes E, for the upper band-wheel shaft, supported by said caps.

In testimony whereof I affix my signature in presence of two witnesses.

WILLIAM M. WILKIN.
